US00D754089S

(12) **United States Design Patent**
Yong et al.

(10) **Patent No.:** **US D754,089 S**
(45) **Date of Patent:** **** Apr. 19, 2016**

(54) **COMMUNICATION DEVICE**

(71) Applicant: **MOTOROLA SOLUTIONS, INC.**,
Schaumburg, IL (US)

(72) Inventors: **Rit Fui Yong**, Singapore (SG); **Nicola Girotti**, Østerbro (DK); **Weng Kong Hor**, Butterworth (MY); **Chor Cheow Ng**, Butterworth (MY)

(73) Assignee: **MOTOROLA SOLUTIONS, INC.**,
Schaumburg, IL (US)

(**) Term: **14 Years**

(21) Appl. No.: **29/504,203**

(22) Filed: **Oct. 2, 2014**

(51) LOC (10) Cl. **14-03**

(52) U.S. Cl.

USPC **D14/137**

(58) **Field of Classification Search**

(57) **CLAIM**

The ornamental design for a communication device, as shown and described.

DESCRIPTION

FIG. 1 is a front perspective view of a design for a communication device;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines that are immediately adjacent to the shaded areas, and define unshaded regions, represent the bounds of the claim, while all other broken lines are directed to environment and are for illustrative purposes only. The broken lines are not part of the claimed design.

1 Claim, 6 Drawing Sheets
